US00D370144S

United States Patent [19]

Insalaco et al.

[11] Patent Number: Des. 370,144

[45] Date of Patent: **May 28, 1996

[54] DRAWER TOWER

[75] Inventors: **Robert W. Insalaco**, Holland, Mich.;
Edgar B. Montague, Charlotte, N.C.[73] Assignee: **Herman Miller, Inc.**, Zeeland, Mich.

[**] Term: 14 Years

[21] Appl. No.: 28,120

[22] Filed: Sep. 7, 1994

[52] U.S. Cl. D6/509; D6/492

CLAIM

The ornamental design for a drawer tower, as shown.

DESCRIPTION

FIG. 1 is a perspective view showing our new design for a drawer tower;
 FIG. 2 is a left and right side view thereof;
 FIG. 3 is a front and rear view thereof;
 FIG. 4 is a top view thereof; and,
 FIG. 5 is a bottom view thereof.
 The broken lines are for environmental purposes only and form no part of the claimed design.
